UNITED STATES PATENT OFFICE.

JOHN D'ALLESINA, OF LONDON, ENGLAND.

CARBURETOR.

Application filed August 7, 1920. Serial No. 401,843.

To all whom it may concern:

Be it known that I, JOHN D'ALLESINA, a subject of the King of England, residing at 213 Queen's Road, Bayswater, London, W. 2, England (whose post-office address is 213 Queen's Road, Bayswater, London, W. 2, England), have invented certain new and useful Improvements in Carburetors, of which the following is a specification.

10 This invention relates to carburetors of the non-float type, that is to say, the type in which the fuel is fed direct to a needle-valve controlled jet nozzle whence it is drawn, together with air from the air-intake, 15 through the choke tube by the suction of the engine.

The object of the present invention is to produce a carburetor of the indicated type in which the fuel and air valves are at all times 20 opened and closed proportionately.

A further object of the invention is to fit the device with means whereby the carburetor is applicable to internal combustion engines working with light or heavy fuel.

25 The invention is illustrated in the accompanying drawings wherein—

Fig. 1 is an elevation,

Fig. 2 is a central vertical section, and

Fig. 3 is a section taken on the line 3—3 in

30 Fig. 1.

Fig. 4 is a sectional view of the three-way valve.

In these drawings A represents the air intake tube, B the fuel supply pipe, C the 35 choke tube, D the jet nozzle, E the conical needle valve, F the fuel valve operating lever, G the throttle valve, and H the throttle valve operating lever.

The fuel valve lever F is pivoted at F' to 40 a frame F² in which the needle valve E is mounted on a spring E'. The end of the lever F is bifurcated and bears upon a nut or block E² on the spindle of the valve E.

The air valve lever H is fixed to an elbow 45 piece H' rotatably mounted on the throttle valve spindle G' and provided with a diametral slot H² to accommodate a diametral pin G² fixed to the valve spindle G' with sufficient play between the pin G² and slot H² to allow a small initial free movement of the lever H thereby ensuring the closure of the jet after the throttle valve has been completely shut off.

The levers F and H are adjustably connected together by means of slide blocks K' 55 fixed by set screws or the like K² to the levers F and H and carrying right and left handed screw-threaded rods K³ engaged by a correspondingly internally screw-threaded link K.

The levers F and H are operated by a rod L connected to one of them, in the example shown the rod L is attached to the lever H.

When used with engines working with heavy fuel the fuel supply pipe B is provided with two branches B' and B² and a three-way valve B⁴ is fitted at their junction with the pipe B. One of the branches, that marked B² in the drawing, is connected with the heavy fuel supply and the other branch, 70 B', is connected to a source of light fuel for starting the engine. In the path of the handle B⁵ of the valve B⁴ is a projection M secured to the elbow H' on the throttle valve lever H so disposed that, when the light fuel supply is opened to the needle valve E, it is impossible to open the throttle valve beyond a certain predetermined distance thereby ensuring a rich initial mixture at the starting of the engine. When the engine has 80 been running on the petrol for a sufficient time the valve B⁴ is operated so as simultaneously to close the petrol branch B' and open the heavy fuel branch B² to the carburetor, thereby removing the handle B⁵ 85 from the path of the projection M on the throttle valve lever which latter may then be operated to open the throttle to its fullest extent.

For the better atomization of the heavier 90 oils, the outlet of the choke tube C is covered with a fine wire gauze net N.

Having fully described my invention, what I claim and desire to secure by Letters Patent is:—

A carburetor for internal combustion engines, comprising a body having an air intake and a jet nozzle, a spring actuated needle valve adapted to normally close said nozzle against the passage of fuel, a lever 100 pivoted to the body adapted to open said needle valve, an inlet valve having an inlet for light fuel and an inlet for heavy fuel, a lever for operating said inlet valve, a throttle valve for controlling the air intake, a 105 lever for operating said throttle valve and

2
formed with a projection, an adjustable connection between the throttle valve operating lever and the needle valve operating lever, so that the opening of the throttle valve is limited by contact of the lever on the inlet valve with the projection of the throttle lever when said inlet valve is in position to admit light fuel.

In testimony whereof I have hereunto set my hand in the presence of two subscribing ¹⁰ witnesses this 22nd day of July 1920.

JOHN D'ALLESINA.
